(57) **CLAIM**

The ornamental design for a digital audio mixer, as shown and described.

DESCRIPTION

FIG. 1 is a top-right-front perspective view of a digital audio mixer showing the new design;

FIG. 2 is a bottom-left-rear perspective view thereof;

FIG. 3 is a front view thereof;

FIG. 4 is a rear view thereof;

FIG. 5 is a left-side view thereof;

FIG. 6 is a right-side view thereof;

FIG. 7 is top view thereof;

FIG. 8 is bottom view thereof; and,

FIG. 9 is a cross-section view taken in the direction of line 9-9 of FIG. 3, without showing internal mechanisms.

Elements depicted in broken lines in the drawings form no part of the claimed design.

Oblique line shading is used in the drawings to denote transparent surfaces.

1 Claim, 9 Drawing Sheets
